UNITED STATES PATENT OFFICE.

HENRY P. SINCLAIRE, OF CORNING, NEW YORK, ASSIGNOR TO H. P. SINCLAIRE & COMPANY, OF CORNING, NEW YORK.

DESIGN FOR A GLASS VESSEL OR SIMILAR ARTICLE.

No. 39,980.

Specification for Design.

Patented May 4, 1909.

Application filed January 21, 1909. Serial No. 473,582. Term of patent 14 years.

To all whom it may concern:

Be it known that I, HENRY P. SINCLAIRE, a citizen of the United States, residing at Corning, in the county of Steuben and State of New York, have invented a new, original, and ornamental Design for a Glass Vessel or Similar Article, of which the following is a specification, reference being had to the accompanying drawing, forming part thereof.

The figure is a plan view of a glass vessel showing my design as engraved thereon.

I claim:

The ornamental design for a glass vessel or similar article, as shown.

HENRY P. SINCLAIRE.
